DESIGN FOR A STEREOSCOPE CASING

Joshua H. Bennett, Rock Island, Ill.

Application June 19, 1933. Serial No. 48,446

Term of patent 7 years

To all whom it may concern:

Be it known that I, JOSHUA H. BENNETT, a citizen of the United States, residing at Rock Island, in the county of Rock Island and State of Illinois, have invented a new, original, and ornamental Design for a Stereoscope Casing, of which the following is a specification, reference being had to the accompanying drawing, forming part thereof.

In the drawing:—

Fig. 1 is a plan view of a stereoscope casing, showing my new design.

Fig. 2 is an end view thereof, looking at the smaller end of the casing.

Fig. 3 is an edge view of the casing, in elevation.

Fig. 4 is an end view thereof, looking at its larger end.

What I claim is,—

The ornamental design for a stereoscope casing, as shown.

JOSHUA H. BENNETT.
